UNITED STATES PATENT OFFICE.

HARRY L. FEASEL, OF PHILADELPHIA, PENNSYLVANIA.

MOP.

1,081,225.

Specification of Letters Patent.

Patented Dec. 9, 1913.

Application filed September 11, 1913. Serial No. 789,274.

To all whom it may concern:

Be it known that I, HARRY L. FEASEL, a citizen of the United States, residing at Philadelphia, in the county of Philadelphia and State of Pennsylvania, have invented new and useful Improvements in Mops, of which the following is a specification.

This invention relates to certain new and useful improvements in mops of the type commonly known as "dustless mops", although not limited thereto.

One of the objects of the invention is to provide improved means whereby the mop proper may be readily attached to or removed from the mop head.

A further object is to provide a mop which is normally circular in form but flexible, whereby it may be made to assume an angular shape if desired.

20 A further object is to provide means by which the mop head may be caused to engage the interior of the mop, said engaging means including means for causing the head to exert an outward pressure to maintain 25 the engagement.

A further object is to provide means by which a flow of water through the mop may be maintained if desired.

30 A further object is to provide improved means for applying oil or the like to the mop material.

The invention will be hereinafter fully set forth and particularly pointed out in the claims.

35 In the accompanying drawing:—Figure 1 is a plan view of the mop head. Fig. 2 is a cross section illustrating the mop and mop head united. Fig. 3 is a bottom plan view of the mop head. Fig. 4 is a side view. 40 Fig. 5 is a plan view illustrating a slight modification.

Referring to the drawing, 10 designates the mop as an entirety, comprising the mop material or brush portion 11 secured within 45 a flexible binding 12, of any suitable material, such as canvas or the like. This mop is made flexible so that the same may assume any desired shape in plan, the normal shape, when disengaged from the mop head, being 50 circular.

The mop head may be of any preferred shape in plan. Referring to Fig. 1, I have shown the same as triangular in form. Each mop head comprises a supporting

plate 15 and a mop engaging plate 16, normally united by screws 17 passing through holes in the supporting plate and engaging threaded bosses 18 of the mop-engaging plate. The screws 17 also serve to secure the coupling 19 to the supporting plate 15. 55 The mop-engaging plate is provided with a section 20 hinged to the main portion of the plate in any suitable manner as indicated at 21. Said section is provided with a threaded opening to receive the threaded 60 stem of a thumb screw 22 passed through a coincident opening in the supporting plate 15.

The supporting plate is provided with an upstanding flange 25, holes 26 being formed 70 in said plate at the intersection of the flange with the main portion of the plate. The plates 15 and 16 are provided with openings 27 coinciding with the bore of the coupling 19, the latter being interiorly threaded at 28 75 to engage an operating handle, and exteriorly threaded at 29 to engage the coupling of a water pipe (not shown) if desired.

In practice when it is desired to attach the mop to the mop head, the thumb screw 22 is 80 disengaged from the movable section 20 so that the latter may swing downwardly on its hinge connection. The mop-engaging plate is then placed within the binding 11 with the joint broken at the hinge 21, and then by 85 pushing downwardly upon the carrier plate, the sections of the mop engaging plate are brought into alignment by a toggle like action that causes the corners of said mop-engaging plate to embed themselves within the 90 inner surface of the binding 12, the binding force being exerted outwardly in such a manner that the mop and mophead are so interengaged that they will not separate. The mop-engaging plate is locked in the ex- 95 panded position. To disengage the parts, the hinged member 20 is released from the thumb screw 22, whereupon a slight upright movement of the carrying plate will permit the mop to be removed.

If it is desired to apply oil or the like to the mop material, the liquid is poured into the receptacle formed by the carrier plate, and will flow through openings 26 onto the brush material 11. In this manner I provide a simple way of evenly applying the oil without danger of soiling the clothing of the operator or waste of material. If in lieu

of oiling purposes it is desired to use the mop as a washer or scrubber, a water pipe may be connected to the coupling 19 so that water will be delivered to the interior of the 5 mop.

Should it be desired to have the mop circular instead of angular the supporting plate and mop-engaging plate are made of the desired shape as illustrated in Fig. 5. 10 In this form the mop engaging plate is provided with two or more pivoted sections 30. The parts are engaged and disengaged in the manner already described.

Having thus explained the nature of my 15 invention, and described an operative manner of constructing and using the same, although without attempting to set forth all of the forms in which it may be made, or all of the forms of its use, what I claim is:—

20 1. The combination with a mop formed of flexible material, of a head provided with means for engaging the interior of said mop with an unyielding expanding pressure.

25 2. The combination with a mop provided with a flexible ring-like binding, of a head provided with a toggle member for engaging the inner wall of said binding.

30 3. As an improvement in mops, a mop head comprising a carrier plate, a mop engaging plate formed of articulated sections, and means for holding said articulated sections in alinement.

35 4. As an improvement in mops, a mop head comprising a carrier plate of angular form, a mop engaging plate of similar form secured thereto and formed of articulated sections provided with mop-engaging cor-

ners, and means for holding the sections of said mop-engaging plate in alinement.

5. As an improvement in mops, a mop- 40 head comprising a carrier plate, a mop engaging plate provided with an articulated section, and a set screw connecting said articulated section and said carrier plate.

6. As an improvement in mops, a mop 45 head comprising a carrier plate provided with a flange and perforations, a mop-engaging plate, and means for uniting said plates.

7. As an improvement in mops, a mop- 50 head comprising a carrier plate, a mop-engaging plate, a coupling, and means for uniting said coupling and said plates.

8. As an improvement in mops, a mop- 55 head comprising a carrier plate, a mop-engaging plate, and a coupling separably connected, said plates being provided with openings coinciding with the bore of said coupling.

9. The combination with a mop formed of 60 flexible material, of a head comprising a carrier plate provided with means for applying liquid to said mop, and a mop-engaging plate connected with said carrier plate and provided with means for engaging 65 said mop with an expanding pressure.

In testimony whereof I have hereunto set my hand in presence of two subscribing witnesses.

HARRY L. FEASEL
